JAMES BURGESS
By Jno. S. Thurman
Attorney

UNITED STATES PATENT OFFICE.

JAMES BURGESS, OF INDIANAPOLIS, INDIANA, ASSIGNOR TO THOMAS HIGHAM, JOSEPH W. JACKSON, AND FRANK W. BALLENGER, OF SAME PLACE.

COLD-IRON SHEARS.

SPECIFICATION forming part of Letters Patent No. 595,028, dated December 7, 1897.

Application filed May 11, 1897. Serial No. 636,122. (No model.)

To all whom it may concern:

Be it known that I, JAMES BURGESS, a citizen of the United States, residing at Indianapolis, in the county of Marion and State of Indiana, have invented certain new and useful Improvements in Cold-Iron Shears; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to an improvement in shears for cutting cold iron and other materials of that class, in which one of the blades is stationary and the other one is moved upward by means of rollers traveling an incline actuated by means of the operating-lever.

5 The object of my invention is to provide a device for cutting metals which produces a compound or triple power upon the cutting-blades without much exertion on the part of the operator.

20 A further object of my invention is to provide an effective, durable, simple, and cheap shears for general workshop use of few parts and comparatively inexpensive to manufacture.

25 With these objects in view my invention still further consists in certain novel details of construction and arrangement of parts to be hereinafter described more fully and pointed out in the claims.

30 It will be obvious to a skilled mechanic that shears of this type constructed as shown will be more effective and require less exertion on the part of the operator than those now in common use.

35 Referring to the drawings which illustrate my invention, Figure 1 is a side elevation, and Fig. 2 is a plan view.

In the drawings, A represents the frame of the machine, having the base B and table C 40 preferably made integral with the frame. Secured to said frame at its upper end is the stationary cutting-blade *a*, screwed thereto. The frame A has the inclines D and E near the bottom, on which the friction-rollers F 45 and G travel, respectively. The incline E is more perpendicular than the incline D. The

object of this is to impart a quick motion to the outer end of the pivoted cutting-arm J, having the roller K, and at the same time increasing the shearing power as the rollers advance. The arm J is pivoted at L and has the cutting-blade R attached to its inner edge at the top. 55

I is the traveling block, having the incline surface H on its top edge, on which the roller K travels. F and G are friction-rollers journaled to its under side.

P is a rack having the teeth *p* on its top side and is pivotally connected to the incline block I at O. 65

T is a friction-roller on which the rack travels.

M is the operating-lever, pivoted to the frame at *n* and having on its lower end the teeth *r*, engaging with the teeth on the rack P. 70

N is a lever pivotally connected to the operating-lever at *h* and to the cutting-arm at *m*. Said connecting-lever is designed to pull the pivoted arm to the open or normal position when the operating-arm is vertical or at rest 75 when the machine is not in use.

S is a plate to cover and to guide the mechanism and is held in place by means of the pivot-bolts *n*, *t*, and L. Said plate is removed in Fig. 1 to clearly illustrate the interior parts, 80 but its outlines are indicated in the dotted lines.

In the operation the metal to be sheared is placed between the knives, and the operating-lever M is pulled downward, which advances the block I up the inclines D and E, 85 which forces the pivoted arm J, carrying the knife-blade R, upward, thus cutting the material.

It is further obvious to a skilled mechanic 90 that many minor changes in the details of construction may be made and substituted for those shown without departing from the scope and spirit of my invention.

Having thus described my invention, what 95 I claim, and desire to secure by Letters Patent of the United States, is—

1. In shears for cutting metals consisting of a frame provided with a base, said frame having a table and a stationary blade rigidly 100 secured thereto, two incline planes placed tandem with the incline on the outer plane

greater than the inner plane, said planes preferably integral with said frame, an arm pivoted to said frame at one end and the opposite end provided with a friction-roller, a cutting-blade secured to said arm, a slideable block having friction-rollers on its lower end traveling in said incline planes of the frame, the top of said block having an incline tapering upward toward its center on which said roller K travels, a friction-roller on said frame, a rack having teeth slideable on said roller and pivotally connected to said incline block, an operating-lever pivoted to said frame and having teeth on its lower end engaging with the teeth in said rack to advance said rack when said lever is pulled downward thereby raising said pivoted arm to close said knives, a lever connecting said lever and arm to pull said arm downward when said lever is in a vertical position, and a plate on one side to cover said mechanism, substantially as shown and described.

2. The herein-described shears for cutting iron and other metals, consisting of a main frame or support having a base and two incline planes placed tandem with the outer incline at a greater angle than the inner one, a block having friction-rollers traveling on said inclines, said block having an incline on its top, an arm pivoted to said frame at one end and a roller at its opposite or outward end traveling on said incline, said arm having a cutting-blade, a roller journaled to said frame, a rack slideable on said roller and pivoted to

said incline block, an operating-lever pivoted to said frame and having teeth on its lower end engaging with said rack, a lever connecting said lever to said arm to pull said arm to open position and a plate on one side to cover said mechanism substantially as shown.

3. The combination of the frame A, having the base B table C and cutting-blade a, the inclines D and E preferably made integral with said frame, the block I having the incline H on its top edge, and rollers F and G traveling on the inclines D and E respectively, the arm J pivoted to said frame at L and having the cutting-blade R, and roller K traveling on said incline H, the roller T journaled to said frame, the rack P pivoted to said block I at O, and slideable on said roller, the operating-lever M pivoted to the frame at n and having the teeth r on its lower end and engaging with the teeth p of the rack P, to advance said rack and press said pivoted arm upward, the connecting-lever N pivoted to said operating-lever at h and to said arm at m to pull said arm downward when said lever is in a vertical position and the plate S secured to the side of said frame by means of suitable bolts substantially as shown and described.

In testimony whereof I affix my signature in presence of two witnesses.

JAMES BURGESS.
